US00D899179S

(12) **United States Design Patent** (10) **Patent No.:** **US D899,179 S**
McConnell et al. (45) **Date of Patent:** **** Oct. 20, 2020**

(54) **FOOD GRINDER**

- (71) Applicant: **WHIRLPOOL CORPORATION**, Benton Harbor, MI (US)
- (72) Inventors: **John W. McConnell**, St. Joseph, MI (US); **Nicholas H. Schutte**, St. Joseph, MI (US); **Brandon T. Mock**, St. Joseph, MI (US)
- (73) Assignee: **Whirlpool Corporation**, Benton Harbor, MI (US)

(**) Term: **15 Years**(21) Appl. No.: **29/734,669**(22) Filed: **May 14, 2020****Related U.S. Application Data**

- (63) Continuation of application No. 29/673,407, filed on Dec. 14, 2018, now Pat. No. Des. 885,822.
- (51) **LOC (12) Cl.** **31-00**
- (52) **U.S. Cl.**

Primary Examiner — Ricky Pham(74) *Attorney, Agent, or Firm* — Price Heneveld LLP(57) **CLAIM**

The ornamental design for a food grinder, as shown and described.

DESCRIPTION

FIG. 1 is a top-front perspective view of a food grinder according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom-back perspective view thereof.

The portions of the article shown in broken line form no part of the claimed design.
